[57] CLAIM

The ornamental design for a one-piece coat-like shirt, as shown and described.

DESCRIPTION

FIG. 1 is a front view of a one-piece coat-like shirt showing my new design;

FIG. 2 is a front elevational view of the bib portion, the coat portion being removed for convenience of illustration;

FIG. 3 is a side view thereof; and

FIG. 4 is a rear elevational view thereof;

FIG. 5 is a rear elevational view of the entire article.
